BUILDING STRUCTURE

Frank E. McCabe, Shaker Heights, Ohio, assignor to The Grabler Manufacturing Company, Cleveland, Ohio, a corporation of Ohio

Application June 1, 1935, Serial No. 24,521

2 Claims. (Cl. 189—85)

This invention relates to building structures, and more particularly to face-work building structures, and has for an object the provision of new and improved structures of this character.

In the drawing accompanying this specification and forming a part of this application, I have shown, for purposes of illustration, embodiments which my invention may assume, and in the drawing:

10 Figure 1 is a fragmentary perspective view of a building structure, embodying the invention, and disclosing parts of the same in horizontal section, and disclosing parts broken away to more clearly illustrate the construction,

15 Figure 2 is an enlarged fragmentary horizontal sectional view, corresponding substantially to the line 2—2 of Figure 1,

Figure 3 is a view similar to Figure 2, corresponding substantially to the line 3—3 of Figure 1,

20 Figure 4 is an enlarged fragmentary horizontal sectional view corresponding substantially to the line 4—4 of Figure 1,

Figure 5 is a fragmentary perspective view, similar to Fig. 1, and disclosing a different embodiment of the invention, while

25 Figure 6 is an enlarged fragmentary horizontal sectional view, corresponding substantially to the line 6—6 of Figure 5.

As shown in Figures 1 through 4 of the drawing, the invention comprises a building structure, wherein a plurality of facing panels 10 are disposed edge to edge and flatwise along the surface of a supporting wall 11, which may be the front wall of a building or the like, and said panels 10 are secured in position along said wall by a plurality of sets of securing means, each set being indicated generally by the reference character 12, and adapted to be positioned between juxtaposed edges of each pair of panels 10; the sets 12 are duplicates in construction and operation and only one of the same will be described in detail.

Each of the sets 12 comprises an elongated member 13, preferably of sheet metal, and channel-shaped in cross-section, having an intermediate portion 14, and flanges 15 along opposite edges adapted to rest against the supporting wall 11. The intermediate portion 14 of the member 13 at intervals along its length is provided with slots 16, each elongated in the direction of the length of the member 13. Associated with each of the slots 16 is an anchoring member 17, comprising a screw-bolt 18, extending through the slot 16, having a head 19 bearing against the outer

face of the intermediate portion 14, and a shank threaded into a wedge part 20, and the wedge part 20 is encased in an expandable sleeve 21, which may be of lead. The wedge part 20 and sleeve 21 may be accommodated in a suitable cavity 22 formed in the supporting wall 11, and rotation of the bolt 18 serves to draw the wedge part 20 inwardly and to expand the sleeve 21 into anchoring engagement with the wall of the cavity 22. When all of the anchoring members 17 have been tightened, the member 13 is fixedly secured to the supporting wall 11, and the slots 16 permit necessary movement incident to expansion and contraction under varying conditions.

The intermediate portion 14 of each of the members 13, at predetermined intervals, preferably at points midway between the anchoring members 17, is provided with openings 23, each of said openings 23 extending through a reinforcing boss 24 formed on the inner side of the portion 14, and each of the openings 23 is threaded for the reception of an actuating screw 25, the shank of which carries a clamping member 26, and the head 27 of which is adapted to bear upon the outer surface of the clamping member 26.

Each of the sets of securing means 12 is adapted to secure juxtaposed edges of a pair of the panels 10 to the supporting wall 11. The panels 10 are formed for cooperation with the securing means 12, each of the panels 10 comprising a rectangular, channel-shaped formation having an intermediate portion 28, an angular web 29 extending along one edge of the portion 28, and an angular web 30 extending along the opposite edge of the portion 28, and the web 29 has an out-turned marginal flange 31 adapted to be clamped between the clamping member 26 and the outer face of the intermediate portion 14 of the member 13, while the web 30 has an out-turned marginal flange 32 adapted to be clamped between the clamping member 26 and the outer face of the intermediate portion 14 of the member 13.

Installation of the face-work structure is preferably effected by first securing a plurality of the members 13 vertically and in spaced relation along the supporting wall 11, through the medium of the anchoring members 17, the members 13 being spaced apart a distance corresponding to the width of the panels it is desired to use. The marginal flanges 31 and 32 of adjacent panels 10 are then inserted between the clamping members 26 and the adjacent outer face of the intermediate portion 14 of the member 13, and the actuating screw members 25 adjusted by a suit-

able tool to clamp the marginal flanges 31 and 32 in position. After all of the clamping members 26 have been adjusted, the space between the webs 29 and 30 of the secured panels 10, may be filled with a suitable filling material, indicated at 33, the heads 19 and 27 of the securing screws providing key means therefor, and in turn being held by said filling material against accidental loosening. Although the securing members 13 5 are shown and described as secured vertically along the supporting wall 11, it will be understood that these members may be disposed horizontally, and the panels 10 secured thereto, or, if desired, the securing members 13 may be arranged both vertically and horizontally to present rectangular formations to which all four edges of the panels 10 may be secured, the panels 10 in this latter case of course having all four edges formed as heretofore described to cooperate with 10 the securing means.

Referring to Figures 5 and 6, a somewhat different embodiment of the invention is disclosed, comprising elongated securing members 34, each having an intermediate portion 35 and flanges 36, the intermediate portion 35 being secured at intervals to the supporting wall 37 by anchoring members 170 identical to the anchoring members 17 heretofore described. A plurality of securing means are provided, each comprising an actuating screw 38 and clamping member 39, identical to the actuating screw 25 and clamping members 26, heretofore described, except that each of the clamping members 39 is somewhat longer than the members 26 for cooperation with panels 40 of 20 a peculiar type.

Each of the panels 40 has angular webs 41 and 42 at opposite edges, the web 41 having an in-turned flange 43, and the web 42 having an in-turned flange 44, the flanges 43 and 44 being 25 adapted to rest against the outer face of the intermediate portion 35 of the member 34. The webs 41 and 42 of adjoining panels are each provided at intervals corresponding to the locations of the securing means, with longitudinally extending slots 45 adapted for the reception of the ends of the clamping members 39, the slots 45 being of sufficient length to permit the clamping members 39 to be rotated about the axis of the actuating screw 38 to facilitate engagement of 30 the clamping members 39 with the slots 45, and when the actuating screws 38 are screwed home, the panels 40 are clamped to the securing members 34. After the panels 40 are in position, suitable filling material, indicated at 46, is employed to fill the cracks between the adjoining edges of the panels.

It will be apparent to those skilled in the art that I have accomplished at least the principal object of my invention, and it also will be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, 10 and that my invention is not limited thereto. 5

I claim:

1. A building structure of the character described, comprising: a support; a plurality of facing members, each having an intermediate portion, an angular web portion, and a marginal flange portion, said facing members being arranged with respect to said support so as to present the angular webs thereof in juxtaposed spaced relation, each of the angular webs having a slot therein; hollow channel-shaped securing means fixedly connected to said support, having flange portions adapted to rest against said support, and having its web disposed outwardly with respect to said support, and against which said facing members are adapted to bear; and a holding device, having means insertable into the slots of the webs of the facing members to hold the same in position with respect to said support, and connecting means extending between said facing members, said securing means and said connecting means being constructed and arranged to render said holding device quickly attachable-detachable as an entirety with respect to said securing means. 20 25 30 35

2. A building structure of the character described, comprising: a support; a plurality of facing members, each having an intermediate portion, an angular web portion, and a marginal flange portion, said facing members being arranged with respect to said support so as to present the angular webs thereof in juxtaposed spaced relation, each of the angular webs having a slot therein; hollow channel-shaped securing means fixedly connected to said support, having flange portions adapted to rest against said support, and having its web disposed outwardly with respect to said support, and against which the said facing members are adapted to bear; and holding means, comprising a screw threaded into the web of said securing means, and carrying a clamping element engageable within the slots in said webs to hold the facing members in position with respect to said support. 40 45 50
